POUR-POINT REDUCTION

Samuel Clyde Vaughn, Berkeley, Calif., assignor to Tide Water Associated Oil Company, San Francisco, Calif., a corporation of Delaware

No Drawing. Application October 25, 1951,
Serial No. 253,201

14 Claims. (Cl. 196—1)

This invention relates to the treatment of hydrocarbon oils for the reduction of pour-point. It is particularly adapted for the reduction of the pour-point of gas-oils, especially those intended for use as fuels for diesel engines, though other oils may be treated in accordance therewith.

Briefly, the invention comprises dissolving hydrogenated castor oil in the oil to be treated at elevated temperature, cooling the solution to precipitate the hydrogenated castor oil, and separating treated oil from the precipitated hydrogenated castor oil. Depending upon the amount of hydrogenated castor oil used, the pour-point of the treated oil may be reduced 40 or more Fahrenheit degrees below that of the original oil. It is believed that the pour-point reduction is due to the removal of petroleum wax from the oil, though it may be due wholly or in part to unknown reactions between the hydrogenated castor oil and petroleum wax contained in the oil.

In the operation in cold climates of diesel engines using hydrocarbon fuels having boiling ranges between approximately 350° F. and 700° F. difficulties are encountered with many otherwise satisfactory fuels due to the precipitation of wax from the oil at low temperatures. The precipitated wax at times causes plugging of the fuel lines and even prevents flow of oil from the fuel tank. Since the more paraffinic types of gas oils are preferred for diesel engine fuels because of their better combustion characteristics, as indicated by high cetane numbers, and since the more paraffinic oils have the greater tendency to precipitate wax, the situation is of major importance in the manufacture of quality diesel fuels. Similar troubles, however, are encountered in furnace oils, and the like, as well as with other oils. Accordingly, a maximum pour-point specification is commonly employed in the purchase of oils intended to be used in cold weather, the pour-point being that temperature at which the oil ceases to flow as determined by ASTM method D97-47.

To produce oils having required low-pour points from stocks of high pour-point, two general procedures are in common use, employed either singly or in combination with each other. In one, the oil is refrigerated to a point where sufficient of the wax precipitates that it can be removed by filtration, thus lowering the pour-point of the filtrate oil. In the second method, certain additives are incorporated in the oil which tend to prevent precipitation of the wax. Both these methods have great disadvantages in the treatment of gas oils, such as diesel fuels. The refrigeration method requires expensive equipment and high operating costs to reduce the temperature of the oil sufficiently for the required amount of dewaxing. Such costs make this procedure economic only with high priced oils. On the other hand, the common pour-point depressant additives have not proven effective in lowering the pour-point of gas oils and diesel oils to the extent required.

The present invention provides a means whereby the

2

pour-point of gas oils may be effectively reduced without resort to refrigeration. The practice of the invention depends upon the solubility of hydrogenated castor oil in the gas oil, or other oil to be treated. At temperatures in the neighborhood of 75° F., hydrogenated castor oil is practically insoluble in hydrocarbon oils, the solubility in most gas oils being less than 0.1% at these temperatures. At temperatures above the melting point of the hydrogenated castor oil, it appears to be completely miscible with most hydrocarbon oils, at least sufficiently so to permit solution of upwards of 20%. In accordance with the invention, an amount of hydrogenated castor oil, depending upon the degree of pour-point reduction required, is dissolved in the oil to be treated at elevated temperature. The homogeneous solution is then cooled to a temperature where the hydrogenated castor oil precipitates from the oil. The precipitated hydrogenated castor oil is then removed from the oil by filtration, centrifuging, or other means, leaving a treated oil of lowered pour-point. If desired, the separated hydrogenated castor oil may be recovered for use in treating subsequent batches of oil by removal of occluded oil and wax by steam and/or vacuum stripping or by extraction with a suitable solvent. The oil so removed may be used as desired, for example as feed stock for catalytic or thermal cracking.

Depending upon the character of the oil to be treated, the character and amount of wax in the oil, and the degree of pour-point reduction required, the amount of hydrogenated castor oil used in the process may vary from less than 1% to over 20%, based on the weight of the oil. With any given oil, the higher rates have been found to give greater reduction in pour-point. On the other hand, the higher rates give lower yields of treated oil due to greater volumes of oil being occluded by the precipitated hydrogenated castor oil. For this reason, it is preferred to use from 1 to 10 parts (by weight) of hydrogenated castor oil per 100 parts of oil when treating diesel fuel oils having, before treatment, pour-points of from 10° to 40° F.

To effect solution of the hydrogenated castor oil in the hydrocarbon oil a temperature of at least about 175° F. will be found necessary. A temperature of about 200° F. is recommended to insure complete solution. Higher temperatures may be used when desired if care is taken to prevent overheating and consequent partial decomposition of the hydrogenated castor oil. In effecting the solution, the oil may be first heated and the hydrogenated castor oil may be mixed therewith either in the solid or molten state. Alternately, the hydrogenated castor oil may be added to the cold hydrocarbon oil and the mixture heated with sufficient agitation to produce a homogeneous solution.

The temperature to which the oil solution of hydrogenated castor oil is cooled should be below about 100° F. to insure substantially complete separation of the hydrogenated castor oil. A temperature of about 75° F. has been found entirely satisfactory in the treatment of diesel fuels. However, still lower temperatures may be found to be convenient or desirable in some instances.

Various techniques are known to the art for separating suspended solid matter from liquids. Any of these may be found suitable, in the practice of the invention, for separating the precipitated hydrogenated castor oil from the hydrocarbon oil. Filtration is preferred, though centrifuging is also effective. Likewise, the technique of washing filter cake with suitable wash liquid to remove occluded filtrate is well known. Though not necessary in the practice of the invention, such washing of the precipitated hydrogenated castor oil may be used as desired. By choice of suitable wash liquid the recovered occluded oil may be found to have a pour-point approximating that of the filtered oil.

In order to re-use the precipitated hydrogenated castor oil for the treatment of subsequent batches of oil, it may be found necessary to remove therefrom wax and/or other materials which have been extracted from the oil. If the oil treated is low boiling, such as gas oil or diesel fuel, such wax and/or other materials will have boiling points sufficiently low that their separation from the hydrogenated castor oil may be effected by steam stripping, preferably with the aid of vacuum to prevent overheating. In any event, the separation may be effected by extraction with a solvent incapable of dissolving the hydrogenated castor oil, for example benzol.

While a particular embodiment of the present invention relates to the reduction of pour-point of low boiling hydrocarbon materials, such as gas oils and diesel fuel, other uses will be readily apparent to those skilled in the art. For example, the pour-point of heavier oils may also advantageously be lowered by means of the present process. In this connection, when treating oils heavier than gas oils, the base oil should be prediluted with a low boiling hydrocarbon or hydrocarbon fraction, such as pentane, octane, or naphtha. For example, in cases involving waxy lubricating oils, dilution in an amount of 1:1 or more has been found to be desirable. The type of material the pour-point of which is to be lowered will in a large measure determine the amount of hydrogenated castor oil to be added.

Hydrogenated castor oil suitable for the practice of the invention, consists primarily of glyceryl-12-hydroxy-stearate, the commercial grades of which contain minor quantities of mixed glycerides of dihydroxystearic and stearic acids as well as other impurities. The invention contemplates the use of either the pure compound or the commercial product, though the latter is preferred.

Following are examples of the invention applied to the treatment of gas oils and diesel fuels, using a commercial grade of hydrogenated castor oil having the following specifications:

Specific gravity, 70° F.	0.98 to 1.00	40
Melting point (ASTM D87-22), °F.	183 to 188	
Acid number	2.0	
Ash, percent	below 0.005	
Iodine number	3 to 6	
Saponification number	175 to 185	45

Example I

To 5 parts by weight of a finished summer grade diesel fuel having a pour-point of 10° F. there was added 1 part of solid hydrogenated castor oil. The mixture was heated with mechanical stirring. At about 175° F. the mixture became homogeneous. After a temperature of 210° F. was reached, the heating was discontinued and the mixture cooled, with continued stirring, to a temperature of about 105° F. During the cooling hydrogenated castor oil began to precipitate from the oil at about 140° to 150° F. and the mixture became mushy at about 120° F. The period of cooling was about two hours. The cooled mixture was filtered, and the filtrate oil was found to have a pour-point of -45° F.

Example II

The procedure of Example I was followed using 25 parts diesel fuel and 2 parts hydrogenated castor oil, except that the final cooling temperature was about 95° F. The filtered oil had a pour-point of -35° F.

Example III

The procedure of Example I was followed using 100 parts diesel fuel and 1 part hydrogenated castor oil. Complete solution was obtained during the heating step at about 175° F. and, during the cooling, precipitation began at about 120° F. The filtered oil had a pour-point of 0° F.

Example IV

The procedure of Example I was followed using 400 parts diesel fuel and 1 part hydrogenated castor oil. Complete solution was obtained at about 175° F., and precipitation did not begin until a few degrees above the final cooling temperature of 105° F. The filtered oil had a pour-point of 5° F.

Example V

Repetition of Example I using 1000 parts diesel fuel and 1 part hydrogenated castor oil and cooling to 95° F. gave no reduction in the pour-point of the filtered oil.

Example VI

To 100 parts by weight of a 30° F. pour-point gas oil, cut from Ventura crude oil, there were added 8 parts hydrogenated castor oil and the mixture heated to 210° F., effecting complete solution of the hydrogenated castor oil in the gas oil. The resulting mixture was cooled, without stirring, to about 70° F. over a period of about 15 hours, during which time the hydrogenated castor oil precipitated. The resulting mixture was filtered, yielding 70 parts of gas oil having a pour-point of -20° F. The filter cake from the filtration was washed with about 100 parts of pentane. The pentane was evaporated from the washings, yielding 25 parts of additional gas oil having a pour-point of -10° F.

Example VII

A 35° F. pour-point gas oil cut from mixed San Joaquin Valley waxy crude oils was treated in accordance with the procedure of Example VI. The resulting yields were comparable with those of Example VI. The combined recovered gas oil had a pour-point of -10° F.

Example VIII

The filter cake produced in a procedure the same as Example VI, except without the pentane washing, was subjected to steam distillation at atmospheric pressure, the temperature in the still reaching 580° F. The distillate was a high pour-point waxy oil which had properties excellently adapted for catalytic cracking charge stock. The residue from the distillation was primarily hydrogenated castor oil which was found suitable for treating a subsequent batch of oil.

In the above examples, and elsewhere in the specifications and claims, the term "diesel fuel" is used to denote a fuel suitable for use in high speed diesel engines composed primarily of gas oil. This is in contrast to heavier hydrocarbon fuels designed for use in low speed diesel engines. The term "gas oil" is used, as commonly employed by the petroleum art, to denote oils having boiling ranges above about 350° F. and below about 750° F.

I claim:

1. A process for reducing the pour-point of hydrocarbon oils which comprises dissolving glyceryl-12-hydroxy-stearate in a hydrocarbon oil, cooling the resulting solution sufficiently to precipitate said glyceryl-12-hydroxy-stearate, and separating oil of lowered pour-point from the resulting precipitate; said cooling and separation of oil being conducted at a temperature above the pour-point of the oil being treated.
2. A process as of claim 1 in which the hydrocarbon oil is a petroleum fraction having a boiling range above about 350° F. and below about 750° F.
3. A process as of claim 2 in which the petroleum fraction is a straight-run petroleum fraction.
4. A process as of claim 1 in which the dissolving step is conducted at a temperature above about 170° F.
5. A process as of claim 4 in which the solution is cooled to below about 105° F. to precipitate the glyceryl-12-hydroxy-stearate.
6. A process as of claim 1 in which the weight of

glyceryl-12-hydroxy-stearate is between about 1% and about 20% of the weight of the oil.

7. A process as of claim 1 in which the glyceryl-12-hydroxy-stearate is hydrogenated castor oil.

8. A process as of claim 1 in which the separation step is conducted by filtration.

9. A process as of claim 1 in which the separation step is conducted by centrifuging.

10. A cyclic process of removing wax from hydrocarbon oils which comprises dissolving glyceryl-12-hydroxy-stearate in a waxy petroleum oil at a temperature above the solution temperature of said stearate in said oil, cooling the resulting solution to a temperature at which said stearate substantially entirely precipitates but above the pour-point of said waxy oil, separating 15 oil of reduced wax content from the resulting precipitate, removing wax and occluded oil from said precipitate, and cycling the remainder of the precipitate to the process to treat a subsequent batch of oil.

11. A process as in claim 10 wherein the occluded 20 oil is removed at least in part by washing with a solvent for the oil incapable of dissolving a substantial amount of the glyceryl-12-hydroxy-stearate.

12. A process as in claim 10 wherein the wax is removed from the precipitate by distillation at reduced partial pressure.

13. A process as in claim 10 wherein the wax is removed from the precipitate by extraction with a wax-solvent incapable of dissolving a substantial amount of the glyceryl-12-hydroxy-stearate.

14. A process as of claim 1 in which the temperature to which the oil-stearate solution is cooled and at which the lowered pour-point oil is separated is between about 75° F. and about 100° F.
